(57) **CLAIM**

We claim the ornamental design for a combination battery, charger and cables for electronic equipment, as shown and described.

DESCRIPTION

FIG. 1 is a front perspective view of a combination battery, charger and cables for electronic equipment, showing our new design in an expanded configuration;

FIG. 2 is a rear perspective view of FIG. 1;

FIG. 3 is a front perspective view thereof, illustrated in a retracted configuration;

FIG. 4 is a rear perspective view of FIG. 3;

FIG. 5 is a top plan view of FIG. 3;

FIG. 6 is a bottom plan view of FIG. 3;

FIG. 7 is a right-side elevational view of FIG. 3;

FIG. 8 is a left-side elevational view of FIG. 3;

FIG. 9 is a front elevational view of FIG. 3; and,

FIG. 10 is a rear elevational view of FIG. 3.

The broken lines showing text in the drawings form no part of the claimed design.
